UNITED STATES PATENT OFFICE.

JOHN H. RESE, OF WASHINGTON, DISTRICT OF COLUMBIA.

BOTTLE CAP OR STOPPER.

No. 892,086.

Specification of Letters Patent. Patented June 30, 1908.

Application filed September 19, 1907. Serial No. 393,720.

To all whom it may concern:

Be it known that I, JOHN H. RESE, a citizen of the United States, residing at Washington, in the District of Columbia, have invented a new and useful Improvement in Bottle Caps or Stoppers, of which the following is a specification.

My invention relates to closures or caps for bottles and like vessels, being especially adapted for use in making paper caps or stoppers for milk bottles; and it has for its object to produce a closure of novel and improved construction that may be made from stock sheet material and shall be provided with a pulling tab.

In the accompanying drawings—Figure 1 is a view of the upper portion of a bottle, part of the neck thereof being represented in section, and a closing cap made according to my invention being shown in place therein. Fig. 2 is a perspective view of a cap. Fig. 3 is a plan view of a sheet of material from which the caps are made, representing the manner of cutting the caps from the stock material.

In the drawings, B represents a bottle such as is now commonly employed for the delivery of milk. Its neck is internally shouldered at b to form an annular seat for the closing cap A which may be, and usually is, formed of paper, it being intended that the caps shall each be used but once and then discarded. The body portion of the cap is in shape a circular disk from the edge of which extends a tab a of peculiar shape. The edge 2 of the disk is circular except for the break that occurs where the tab a joins the body. This tab under normal conditions, lies in the plane of the body A, though when put in place in a bottle it is bent upward as indicated in Fig. 1. To facilitate this bending I prefer to score the disk on the upper surface, along a line that completes the edge circle 2, as indicated at 6. The tab tapers towards its outer end 5, and has its opposite edges 4 and 5 curved, the line of each side or edge being a reverse curve, as compared with the peripheral curve of the body A, and flowing or springing therefrom, the radii of the several curves, 2, 4, and 5, being of equal length.

The lower or seating surface of the stopper is preferably curved or rounded along the edge 2; but this edge, in the plane of the other surface is comparatively sharp. I have found that when thus formed the caps

may be better seated in the bottle neck than when the edges are square cut.

There are several advantages incident to a disk stopper or cap of the construction or form described. The tab is comparatively long permitting it to be easily grasped when the cap is seated in the bottle neck, and its outer exposed end is slender so that should it be engaged by some moving object it will yield without unseating the stopper. On the other hand the tab has strength where strength is required, that is, along the line of its juncture with the body A. Further, the peculiar shape is of advantage in the manufacture of the caps, as it permits of nearly all of a piece of stock material being utilized when the caps are cut out, as clearly indicated in Fig. 3, the material between adjacent bodies A constituting the tabs a. Another practical advantage is that the tools employed in cutting the disks are of simple shape and may be easily made without requiring the use of especially devised and expensive machinery.

While I have described a sealing disk made of paper and adapted to be used as a milk bottle stopper, I wish it understood that my invention is not limited to any particular use or adaptation of the stopper or closure, nor to its being formed of any particular material.

What I claim is:

1. A sealing cap or closure comprising a disk of suitable material, the body portion of which is of circular outline and from the edge of which extends a tab, the opposite sides or edges of the latter being formed on reverse curves springing from the peripheral curve of the main body portion of the cap, and uniting at the outer end of the tab, substantially as set forth.

2. A sealing cap or closure comprising a disk of suitable material, the body portion of which is of circular outline and from the edge of which extends a tab a, the opposite edges of the latter being formed on reverse curves springing from the peripheral curve of the main body A and the radius of each of the said reverse curves being equal in length to the radius of the peripheral curve of the part A, substantially as set forth.

3. A cap or closure for a bottle comprising a suitable paper disk, the body portion, A, of which is of circular outline and from the edge of which extends a tab a, the material

of the closure being scored along the line of juncture of the body A, and a tab, and the opposite edges of the tab being formed on reverse curves springing from the peripheral curve of the main body portion A, and uniting at the outer end of the tab, substantially as set forth.

4. A sealing cap or closure comprising a disk of suitable material, the body portion

of which is of circular outline and from the edge of which extends a pulling tab, the seating surface of the cap or closure being curved or rounded along its edge, substantially as set forth.

JOHN H. RESE.
